Primary Examiner—Melanie H Tung

(74) *Attorney, Agent, or Firm*—Sterne, Kessler, Goldstein & Fox PLLC

(57) **CLAIM**

The ornamental design for a graphical user interface for a display screen or portion thereof, as shown and described.

DESCRIPTION

The FIGURE is a front view of a graphical user interface for a display screen or portion thereof showing my new design.

The broken lines showing a display screen or portion thereof and other elements form no part of the claimed design.
